ALLAN COATS, OF NEWARK, NEW JERSEY.

VALVE.

1,150,576.

Specification of Letters Patent. Patented Aug. 17, 1915.

Application filed October 4, 1910. Serial No. 585,175.

To all whom it may concern:

Be it known that I, ALLAN COATS, a subject of the King of Great Britain, residing at Newark, in the county of Essex and State of New Jersey, have invented certain Improvements in Valves, (for which I filed an application in Great Britain, October 4, 1909, No. 22,534,) of which the following is a specification.

10 This invention relates to valves of the combined fluid and mechanically operated type, such as are used for steam pumps and the like.

15 The objects of the invention are to simplify the construction, to render more certain the operation, and to reduce the wear, in combined fluid and mechanically operated valves, and to obtain other advantages and results as may be brought out in the 20 following description.

Referring to the accompanying drawings, in which like numerals of reference indicate the same parts throughout the several figures, Figure 1 is a plan of the valve proper and operating caps, showing the said valve proper at one end of its travel; Fig. 2 is a central longitudinal section of the complete valve and casing taken on line 2—2 of Fig. 1 with the valve in the same position; Fig. 3 is a cross section of the valve on line 3—3, Fig. 1, looking toward the right hand end of said figure, and Fig. 4 is a cross section on line 4—4, Fig. 2, looking toward the left hand end of said figure.

25 In said drawings, A indicates a central spindle which receives a circumferentially reciprocating motion or oscillation from any reciprocating part of the pump mechanism by means of any suitable connection which 30 mechanical skill may suggest. I have shown, to illustrate oscillating means, one end of the spindle projecting and provided with a crank arm A₂ which can be suitably connected to the pump mechanism to turn 35 the spindle back and forth through a small arc. On this spindle A are fastened caps B and C, their relative position on the spindle being fixed by means of keys V, V₁, of the like. To the outsides of these caps are 40 fastened plates D and E. These plates serve the double purpose of forming covers for the exhaust shooting passages F and G in the caps B and C, respectively, and also as a means to partly throttle the main steam 45 passages L, L₁ to the pump, should this be desired. This throttling is done by having

said plates long enough so that each plate always overlies, longitudinally of the valve, that transverse portion of the valve proper, H, in which the steam passage L, or L₁, 50 nearest the said plate is located, and then making the length of said ports transversely of the valve in such relation to the width of the plates, and so located circumferentially with respect to said plates, that as the caps 55 oscillate, their said plates cover the active inlet port and uncover the other or idle port as the pump piston gets near the end of its stroke. This serves the usual purpose of a cut off, but it is preferable that the closure be not complete lest the piston should 60 not properly complete its stroke and thus fail to oscillate the caps to shoot the valve. The plates D, E, do not therefore necessarily bed on the main steam valve or shooting valve H, but are spread slightly therefrom, as shown in Fig. 2.

The caps B and C are closed at their ends away from each other and in their circumferential walls they have exhaust shooting 65 passages F, G, and steam passages J, K, respectively. Said exhaust shooting passages F, G, as already stated, are covered by the plates D, E, while the steam passages J, K have a clear way through the caps B, C. 70

Inside the caps B, C, the main steam valve H works. This valve H has suitable steam passages L, L₁, and M, M₁, and exhaust passages N, N₁, connected to the pump cylinder, and is shown with a central hole 75 to admit driving spindle A, though any other method of circumferentially reciprocating the caps B and C may be employed.

In the main steam valve H, suitable steam shooting ports R and S, and exhaust steam 80 shooting ports P, Q, are provided, so that the latter, P, Q, are connected to the main exhaust passage T of the valve H and the former, R, S, are connected to the chambers inclosed between the caps B, C, and the 85 valve H.

The action of the mechanism is as follows: When the central spindle A is partially rotated, the sleeves B, C rotate with it, but the valve H does not, being held up against the 90 steam cylinder face by the steam pressure. As shown in Fig. 1, the opening J in cap B admits steam by means of passage R to the left hand of valve H. When further travel takes place, the passage G cut in the cap 95 allows steam from between the right hand of valve H and the cap C to escape by

means of the passages G, Q to the main exhaust chamber T, and thus causes the valve H to shoot over to the right in direction of cap C. Steam is thus admitted by means of 5 port L to the main pump passage M₂, leading to one end of the cylinder, while the passage M₃ from the other end is connected by means of the passages N, N₁ to exhaust X. The piston then commences its stroke, and 10 when near the end the reciprocating mechanism commences to rotate the spindle A in the opposite direction by means of lever A₂.

To prevent the valve H from sticking on its seat, pins W, X₂, or their equivalent, 15 may be set so that the plates D, E alternately strike the pins W, X₂ and allow the valve to shoot. These pins W, X₂ also prevent the valve H from moving materially from its correct radial position.

20 On the caps B, C being rotated in the opposite direction, the corresponding ports on the opposite side of the caps come into operation, and at the proper time the valve H shoots back to its original position.

25 It will be noted that the ports G, Q and F, P have meeting ends which are inclined or oblique to the direction of movement of the ports in coming into registration, and thus a greater area of registration is more 30 quickly secured and a more quick response of the valve proper.

Having thus described the invention, what I claim is:

1. The combination with a fluid-operated 35 pump, of a shooting valve having caps at either end, means to circumferentially reciprocate said caps, and means to control by means of the movement of said caps the admission and exhaust of fluid to the spaces 40 inclosed between the ends of said shooting valve and caps.

2. The combination with a fluid-operated 45 pump, of a shooting valve having caps at either end, means to circumferentially reciprocate said caps, and means to partly throttle by means of the movement of said caps the flow of fluid to the main cylinder when the piston approaches the end of its stroke.

50 3. The combination with a fluid operated pump, of a shooting valve having caps at either end, means to circumferentially reciprocate said caps, and means coating with said caps to prevent said shooting valve from sticking to its seat.

55 4. A valve of the character described, having a shooting valve, caps for the ends of said shooting valve, and means for oscillating said caps to admit a pressure fluid to one end of the shooting valve and exhaust it from the other end and then admit to the second end and exhaust from the first end.

60 5. A valve of the character described, having a longitudinally reciprocable valve proper with ports, caps slidably fitting the

ends of said valve proper and having ports, and means for oscillating said caps to move the ports of said caps operatively with respect to the ports of the valve proper.

6. A valve of the character described, 70 having a shooting valve, caps for the ends of said shooting valve, means for oscillating said caps, and means for imparting a portion of the oscillation of said caps to said shooting valve.

7. A valve of the character described, 75 having a shooting valve, caps for the ends of said shooting valve, means for oscillating said caps, and stops on the shooting valve adapted to be engaged by said caps at opposite ends of their arc of oscillation.

8. A valve of the character described, 80 having a shooting valve, caps for the ends of said shooting valve, means for oscillating said caps, and stops on said shooting valve at opposite ends of the arc of oscillation of said caps adapted to limit turning of the shooting valve.

9. A valve of the character described, 85 having a shooting valve, caps for the ends of said shooting valve, means for oscillating said caps, plates projecting longitudinally from said caps, and stops on the shooting valve at opposite sides of said plates.

10. In a valve of the character described, 90 the combination with a valve proper, and means for admitting pressure fluid to move said valve proper, of means for automatically moving said valve in another direction to prevent it from sticking.

11. In a valve of the character described, 95 the combination with a longitudinally reciprocable valve proper, and means for admitting pressure fluid to move said valve proper, of means for automatically imparting to said valve proper a rotary movement to release it from sticking.

12. The combination of a valve proper 100 having passages opening circumferentially and provided with an oblique wall, caps for the ends of said valve proper having passages adapted to register with said valve passages and provided with similar oblique walls, and means for oscillating said caps so as to move said oblique walls of the passages into and out of registration in connecting and disconnecting said passages.

13. In a valve of the character described, 105 the combination of a shooting valve having inlet ports separated both longitudinally and circumferentially, caps for the ends of said shooting valve, means for oscillating said caps, and plates on said caps adapted to throttle said ports alternately.

14. In a valve of the character described, 110 the combination of a shooting valve having inlet ports separated both longitudinally and circumferentially, caps for the ends of said shooting valve, means for oscillating said caps, and plates on said caps extending 115

120 130 135

longitudinally of the valve one over each port and adapted to alternately partially close said ports as the caps oscillate.

15. In a valve of the character described, 5 the combination of a shooting valve having inlet ports separated both longitudinally and circumferentially, caps for the ends of said shooting valve, means for oscillating said caps, and plates on said caps extending longitudinally of the valve one over each port, said plates being wider than said ports and spaced from the valve.

16. In a valve of the character described, 15 the combination of a shooting valve having inlet ports, caps for the ends of said shooting valve, means for oscillating said caps, plates

on said caps adapted to throttle said ports alternately, and stops on the shooting valve at opposite sides of said plates to limit turning of said shooting valve. 20

17. In a valve of the character described, the combination of a shooting valve having inlet ports, caps for the ends of said shooting valve, means for oscillating said caps, plates on said caps adapted to throttle said ports 25 alternately, and stops on the shooting valve at opposite sides of said plates and adapted to be engaged thereby as the caps oscillate.

ALLAN COATS.
